UNITED STATES PATENT OFFICE

2,474,264

ADJUSTABLE SEAT STRUCTURE

Anton Lorenz, Buffalo, N. Y.

Application October 27, 1944, Serial No. 560,553

11 Claims. (Cl. 155—45)

1

My invention relates to articles of furniture, and more particularly to an article of furniture, wherein a structure including a seat, a back-rest and means connecting said back-rest with said seat is swingably mounted on a support and controlling means are arranged for controlling the movements of a leg-rest pivoted to the seat, during a movement of the structure from one position into another one.

An object of my invention is to provide an article of furniture of above described type, wherein the controlling means acting on the leg-rest may cause a change in the angle between the leg-rest and the seat when the seat of the structure is moved from its sitting position into a rearwardly inclined position.

Another object of my invention is to provide an article of furniture of above described type, wherein the angle between the leg-rest and the seat may be increased to such a degree, that the leg-rest is brought into alignment with the seat when the latter is in its extreme rearwardly inclined position.

A further object of my invention is to provide an adjustable chaise-longue, wherein the seat, back-rest and leg-rest are movable relative to each other.

A further object of my invention is to improve upon the art of reclining articles of furniture as now ordinarily made.

With the above and other objects of the invention in view, the invention consists in the novel construction, arrangement and combination of various devices, elements and parts, as disclosed hereinafter, certain embodiments of the same being described in the specification and being illustrated in the accompanying drawings forming part of this specification, wherein:

Fig. 1 is a side elevational view of an embodiment of a convertible chaise-longue according to the invention, some parts being broken away.

Fig. 2 is a side elevational view of the chaise-longue shown in Fig. 1, wherein, however, the movable members are in a different position, some parts being broken away.

Fig. 3 is a side elevational view of another embodiment of a chaise-longue according to the invention, some parts being broken away.

Fig. 4 is a side elevational view of still another embodiment of a chaise-longue according to the invention, some parts being broken away.

Referring now to Figs. 1 and 2, 210 generally indicates the support of an article of furniture known in the trade as a chaise-longue. 212 generally indicates a back-rest and 214 indicates a

2

seat. Said back-rest 212 and the rear end of said seat 212 are pivotally connected with each other and the support 210 at 216. A pair of connecting links 218 and 220 is arranged on each side of the chaise-longue or lounger. The connecting link 218, hereinafter called a top connecting link, forms an arm-rest and is pivotally connected at 222 with the connecting link 220, hereinafter called a front connecting link. The rear end of each top connecting link 218 is pivoted at 224 to an intermediate point of the back-rest 212 above the seat 214. The lower end of each front connecting link 220 is pivoted to the front portion of the seat 214 at 226. A guiding means or guiding link 230 is pivoted with one end to the support at 232 and with the other end to the front connecting link 220 at 254. Thus, the article comprises a constrained complex linkage having five movable links 212, 218, 220, 214, 230 and one stationary link formed by the portion of the support between the pivots 216 and 232.

The sitting position of the seat 214 and the movable members connected therewith may be limited by a stop 262 mounted on the support 210.

25 A leg-rest 236 is pivotally connected with the front end of the seat 214 at 238. The movements of said leg-rest 236 are controlled by a rod-like controlling link 240, one end of which is pivotally mounted on the support 210 at 232. The other end of said controlling link carries controlling means in the shape of a rotatable roller 256 loosely engaging the surface of the leg-rest 236 to effect movements of the latter in coordination with said controlling link. Instead of the roller shown in Figs. 1 and 2, the end of the controlling link 240 could be provided with a cam or could be in direct contact with the surface of the leg-rest 236 for sliding along the surface of the leg-rest. The controlling link 240 is guided by a bar-like guiding member 258, one end of which is pivoted to the seat at 238, the other end of which is pivoted to the controlling link 240 at 260.

When the seat 214 is swung into a reclined position, for example into the extreme reclined position shown in dash and dot lines in Fig. 1, by moving the back-rest 212 about its pivot 216, the controlling link 240 is swung about its pivot 232 by means of the guiding member 258 pivotally connected with the seat. Such a swinging movement of the controlling link 240 causes an increase of the angle between the leg-rest 236 and the seat 214 from the sitting position to the reclined position. During said swinging movement 55 of the controlling link 240, the roller 256 rolls

along the surface of the leg-rest 236. According to the embodiment shown in Fig. 1, the leg-rest 236 is in alignment with the seat 214, when the latter is in its extreme reclined position. The movable members of the article may be held in any desired position by means of a locking device 252 arranged on the pivot 222 between the top connecting link 218 and the front connecting link 220.

At least one of the pivotal connections of the complex linkage of the article shown in Figs. 1 and 2 is disengageable. According to the embodiment shown in said figures, for example, the pivotal connection 224 between the back-rest 212 and the top connecting link 218 and the pivotal connection 254 between the front connecting link 220 and the guiding link 230 may be disengaged. Upon such a disengagement, the seat 214 is held in the substantially horizontal position shown in Fig. 2 by a holding member or stop 262 mounted on the support 210, and the guiding link 230 and pair of connecting links 218, 220 may drop into the position shown in Fig. 2. Furthermore, the back-rest 212 may be swung into a substantially horizontal position, substantially in alignment with the seat 214, which is limited by another holding member 264, mounted on the support for cooperation with the back-rest. In addition to above described disengagement, the pivotal connection 260 between the guiding member 258 and the controlling link 240 may be disengaged, whereupon the controlling link 240 may be lifted for a lifting of the leg-rest 236 into a substantially horizontal position in alignment with the seat 214, until the bore 266 (see Fig. 2) of the controlling link 240 registers with a bore 268 (see Fig. 1) arranged on the support 210. When said bores 266 and 268 are in register with each other, a pin 270 (see Fig. 2) may be inserted into said bores, so that the controlling link 240 and the leg-rest 236 are held in the position shown in Fig. 2. If the members 212, 214, 236 are in the position shown in Fig. 2, they are substantially in alignment with each other, so that the article is converted into a bed-like or couch-like furniture.

When the article shown in Figs. 1 and 2 is converted into a bed-like furniture, the leg-rest 236 may be held in the horizontal position by another holding arrangement than that described above. For example, the bore 268 could be arranged in the guiding member 258 at the proper place, so that, upon an insertion of the pin 270 into the registering bores 266, 268, the leg-rest 236 is held in its position by the guiding member 258 connected with the controlling link 240.

Furthermore, the article shown in Figs. 1 and 2 is equipped with means for varying and adjusting the effective length of the controlling link 240. For this purpose, the controlling link 240 is in the shape of a telescopic rod comprising the members 241, 243 slidably engaged with each other and held in an adjusted relative position by a set screw 245, and the support 210 as well as the guiding member 258 are provided with a series of holes 261. If, for example, the telescopic controlling link 240 is shortened, the angle between the leg-rest and the seat is reduced in the sitting position, and the leg-rest comes into alignment with the seat only when the seat is at a greater angle to the horizontal plane than that shown in Fig. 1 for the reclined position. On the other hand, if the telescopic controlling link 240 is lengthened, the angle between the leg-rest and the seat is increased in

the sitting position, and the leg-rest comes into alignment with the seat when the seat is at a smaller angle to the horizontal plane than that shown in Fig. 1 for the reclined position. Similar results may be obtained by selecting different holes 261 for the pivotal connections of the telescopic controlling link 240 without a change in the length of the telescopic controlling link 240 or in combination with such a change in the length.

According to the embodiment shown in Fig. 3, the back-rest 412 and the seat 414 form an integral member generally indicated by 416; therefore, the back-rest 412 is rigidly connected with the seat 414. The member or structure 416 is swingably mounted on the support 410 at 416. The leg-rest 436 pivotally mounted on the seat 414 at 438 is controlled by the following controlling mechanism: One end of a controlling link 440 is pivotally mounted on the support at 446; the other end of said controlling link 440 is connected with the leg-rest 436 by means of a controlling member 472, one end of which is pivoted to the controlling link 440 at 474, the other end of which is pivoted to the leg-rest 436 at 476. The controlling link 440 is guided by a guiding member 458, one end of which is pivoted to the controlling link at 460, the other end of which is pivoted to the seat 414 at 478. Apparently, the controlling member or controlling means 472 positioned between the controlling link 440 and the leg-rest serves to effect movement of the leg-rest in coordination with said controlling link.

The sitting position of the movable members 35 of the article is limited by a stop 448 arranged on the support 410 for cooperation with the seat 414. The extreme reclined position of the movable members of the lounger is limited by a stop 450, arranged on the support 410 for cooperation 40 with the back-rest 412.

When the member 470 comprising the back-rest and the seat is swung into a reclined position, the angle between the leg-rest 436 and the seat 414 is increased by means of the action of 45 the controlling link 440, which is lifted by the guiding member 458 and controls the leg-rest 436 through the medium of the controlling member 472. Fig. 3 illustrates an intermediate reclined position and does not show the extreme 50 reclined position.

According to Fig. 3, a stop 480 is arranged at the end of the controlling link 440. This stop 480 comes in engagement with the controlling member 472, as soon as, during a movement of 55 the movable members of the article from the sitting position into a reclined position, the controlling member 472 comes into alignment with the controlling link 440, so as to prevent the controlling member from a further rotation about the 60 pivot 474 relative to the controlling link.

The controlling mechanism 549, 558, 572 of the leg-rest 536 of the chaise-longue shown in Fig. 4 substantially corresponds to the controlling mechanism of the leg-rest shown in Fig. 3. However, according to Fig. 4, said controlling mechanism is used in combination with a chaise-longue having a constrained complex linkage. According to Fig. 4 a back-rest 512 and the rear end of a seat 514 are pivotally connected with 65 each other and the support 510 at 516. The back-rest 512 has a lower extension 532. Said extension 532 rigidly connected with the back-rest 512 projects downwardly beyond the pivotal connection 516 between the back-rest and the support. A pair of connecting links 518, 520 pivot-

ally connected with each other as 522 is arranged below the seat. The rear end of the connecting link 518 designated hereinafter as a lower connecting link is pivoted to the extension 582 at 524; the upper end of the connecting link 520 hereinafter called the front connecting link is pivotally connected with a lug on the seat 514 at 526.

The movements of the back-rest 512 with its extension 582, the lower connecting link 518, the front connecting link 520 and the seat 514 are controlled by a guiding link 530; one end of said guiding link is pivoted to the pivotal connection 522 between the lower connecting link 518 and front connecting link 520, the other end of said guiding link is pivotally connected to the support 510 at 532. Thus, the article comprises a constrained complex linkage having five movable links 514, 582, 518, 520, 530 and one stationary link formed by the portion of the support 510 between the pivots 516 and 532.

The leg-rest 536 is pivoted to the seat 514 at 538; and the controlling link 540 is pivoted to the support 510 at 546.

When the back-rest 512 is swung about the pivot 516, the movable members of the constrained complex linkage are brought from the sitting position shown in full lines into a reclined position, for example into the extreme reclined position shown in dash and dot lines. The seat 514 forming a part of said constrained complex linkage is swung about the pivot 516 and causes a swinging of the controlling link 540 about the pivot 546 through the medium of the guiding member 558 pivoted at its ends to the seat 514 and the controlling link 540 respectively. Such a swinging of the controlling link 540 causes a change in the angle between the leg-rest 536 and the seat 514 through the medium of the controlling member 572.

The sitting position of the movable members of the article is limited by a stop 548 mounted on the support 510 for cooperation with the lower extension 582 of the back-rest 512. The extreme reclined position of said movable members may be limited by a stop 550 swingably mounted on a transverse rod 564 of the support 510, when the stop is in the position shown in Fig. 4 for cooperation with the back-rest 512.

Fig. 4 illustrates means for varying and adjusting the effective length of the controlling member 572. For this purpose, the controlling member 572 is composed of two telescopically arranged members 584 and 586, which may be adjusted in any desired position relative to each other by means of a set screw 588. Furthermore, the leg-rest 536 and the controlling link 540 are provided with series of holes 590 which may be used for selective pivotal connections of the telescopic controlling member 572 with the leg-rest and the controlling link respectively. As will be readily understood, this arrangement enables the user of the chair to adjust the angle between the leg-rest and the seat to any desired degree. When the telescopic controlling member 572 is of the adjusted length shown in Fig. 4 and when the ends of said telescopic controlling member are pivoted to the points of the leg-rest 536 and the controlling link 540 as shown in said Fig. 4, the angle between the leg-rest and the seat will be increased during a movement of the movable members of the lounger from the sitting position into a reclined position, and the leg-rest will be in alignment with the seat when the latter is in its extreme reclined position. When, for example,

the length of the controlling member 572 remains unchanged, when the upper end thereof, however, is pivoted to the last hole on the right hand side of the series of holes 590 of the leg-rest 536, the angle between the leg-rest and the seat will be decreased during such a movement of the movable members, and the leg-rest will be in a substantially horizontal position when the seat is in its extreme position.

In view of the variable arrangement of the telescopic controlling member 572 in the system, the stopping means for limiting the rotation of the controlling member 572 about its pivot 514 is likewise adjustable. According to Fig. 4, the enlarged end 592 of the controlling link 540 is provided with a slot 594. One end of a pin or stop 596 having a shoulder (not shown) resting on the surface of said enlarged end 592 of the controlling link 540 is adjustably inserted into said slot 594 and projects therefrom; the pin 596 may be held in an adjusted position by means of a nut 598 or the like screwed on said projecting end of the pin 596. The other end of said pin or stop projects from said slot at a right angle to the enlarged end 592 of the controlling link 540, so that it may engage the telescopic controlling member 572 in its extreme position as shown in dash and dot lines. According to the showing of Fig. 4, the pin 596 is held in the uppermost corner of the slot 594 by means of the nut 598. If, however, the controlling member 572 is pivoted to another point of the leg-rest, for example to the last hole on the right hand side of the series of holes of the leg-rest as described above, the pin 596 is brought into a lower position in the slot 594 and is held therein by the nut 598, so that it may properly engage the controlling member 572 in the extreme position thereof.

40 The article shown in Fig. 4 may be converted into a bed-like or couch-like furniture by disengagement of at least one of the pivotal connections 522, 524, 526 of the constrained complex linkage and by swinging the stop 550 out of 45 the path of the back-rest 512. After such a disengagement of one or more pivotal connections, the seat 514 is held in a horizontal position by means of a stop 562 arranged on the support 510, and the back-rest 512 may be swung into a horizontal position limited by the transverse rod 564. Furthermore, the telescopic controlling link 586 may be lengthened, so that it holds the leg-rest 536 in alignment with the seat 514 in a horizontal position.

55 I have described preferred embodiments of my invention, but it is understood that numerous changes and omissions may be made without departing from the spirit of my invention.

For example, the controlling mechanism of the 60 leg-rest shown in one of the figures may be used in combination with a seat structure shown in any other figure of the drawings or with any other seat structure comprising a swingable seat.

Furthermore, while the controlling mechanism 65 controlling the movements of the constrained complex linkage shown in the drawings comprises a guiding link, the present invention may also be applied to articles of furniture wherein the controlling mechanism controlling the movements of the constrained complex linkage includes different controlling means operatively connected with the support and a movable member of the linkage.

Moreover, instead of a telescopic controlling 70 member or telescopic controlling link other means

may be used for changing the effective length of the controlling link or controlling arm respectively.

Moreover, any other suitable type of locking means for locking the movable members of the article in a desired position may be used instead of the locking device shown in the drawings.

The drawings show the invention only in the way of certain examples; the invention may be applied to various other types of articles of furniture as well.

What I claim is:

1. A reclining article of furniture comprising: a support, a structure including a seat, a back-rest and means connecting said back-rest with said seat for controlling movements of the back-rest and the seat in dependence on each other, said structure being swingably mounted on said support, stopping means arranged on said support for limiting the sitting position of said structure, a leg-rest pivotally connected with the front portion of said seat, a controlling link pivoted to said support at one of its ends, a guiding member, one end of said guiding member being pivoted to said seat, the other end of said guiding member being pivoted to an intermediate point of said controlling link, and controlling means positioned between the other end of said controlling link and said leg-rest to effect movement of the leg-rest in coordination with said controlling link whereby movements of said leg-rest are controlled in dependence on movements of said seat.

2. In a reclining article of furniture as claimed in claim 1, means whereby the effective length of the controlling link may be varied and adjusted.

3. A reclining article of furniture comprising: a support, a structure including a seat, a back-rest and means connecting said back-rest with said seat for controlling movements of the back-rest and the seat in dependence on each other, said structure being swingably mounted on said support, stopping means arranged on said support for limiting the sitting position of said structure, a leg-rest pivotally connected with the front portion of said seat, a controlling link pivoted to said support at one of its ends, a guiding member, one end of said guiding member being pivoted to said seat, the other end of said guiding member being pivoted to an intermediate point of said controlling link, and a controlling member, one end of said controlling member being pivoted to the other end of said controlling link, and the other end of said controlling member being pivoted to said leg-rest.

4. In a reclining article of furniture as claimed in claim 3, a stop mounted on said controlling link for abutting cooperation with said controlling member so as to limit the extreme position thereof.

5. In a reclining article of furniture as claimed in claim 3, means whereby the effective length of said controlling member may be varied and adjusted.

6. A reclining article of furniture comprising in combination: a support, a constrained complex linkage having a plurality of movable links and at least one stationary link, at least a portion of said support being included in said constrained complex linkage as said stationary link, said movable links including a seat, a back-rest and a plurality of connecting links, said connecting links being connected to each other, to said seat and to said back-rest, means pivotally connecting said seat and said back-rest to said support, guid-

ing means connected to said support and engaged with at least one of said connecting links, stopping means arranged on said support for limiting the sitting position of said seat, a leg-rest pivotally connected with the front portion of said seat, a controlling link pivoted to said support at one of its ends, a guiding member, one end of said guiding member being pivoted to said seat, the other end of said guiding member being pivoted to an intermediate point of said controlling link, and controlling means positioned between the other end of said controlling link and said leg-rest to effect movement of the leg-rest in coordination with said controlling link whereby movements of said leg-rest are controlled in dependence on movements of said seat.

7. A reclining article of furniture comprising in combination: a support, a constrained complex linkage having a plurality of movable links and at least one stationary link, at least a portion of said support being included in said constrained complex linkage as said stationary link, said movable links including a seat, a back-rest and a plurality of connecting links, said connecting links being connected to each other, to said seat and to said back-rest, means pivotally connecting said seat and said back-rest to said support, guiding means connected to said support and engaged with at least one of said connecting links, stopping means arranged on said support for limiting the sitting position of said seat, a leg-rest pivotally connected with the front portion of said seat, a controlling link pivoted to said support at one of its ends, a guiding member, one end of said guiding member being pivoted to said seat, the other end of said guiding member being pivoted to an intermediate point of said controlling link, and controlling means positioned between the other end of said controlling link and said leg-rest to effect movement of the leg-rest in coordination with said controlling link whereby movements of said leg-rest are controlled in dependence on movements of said seat.

8. A reclining article of furniture comprising: a support, a structure including a seat, a back-rest and means connecting said back-rest with said seat for controlling movements of the back-rest and the seat in dependence on each other, said structure being swingably mounted on said support, stopping means arranged on said support for limiting the sitting position of said structure, a leg-rest pivotally connected with the front portion of said seat, a controlling link pivoted to said support at one of its ends, and a guiding member, one end of said guiding member being pivoted to said seat, the other end of said guiding member being pivoted to an intermediate point of said controlling link, and the other end of said controlling link being in shiftable engagement with said leg-rest whereby movements of said leg-rest are controlled in dependence on movements of said seat.

9. A reclining article of furniture comprising in combination: a support, a constrained complex linkage having a plurality of movable links and at least one stationary link, at least a portion of said support being included in said constrained complex linkage as said stationary link, said movable links including a seat, a back-rest and a plurality of connecting links, said connecting links being connected to each other, to said seat and to said back-rest, means pivotally connecting said seat and said back-rest to said support, guiding means connected to said support and engaged with at least one of said connecting links, stopping means arranged on said support

for limiting the sitting position of said seat, a leg-rest pivotally connected with the front portion of said seat, a controlling link pivoted to said support at one of its ends, and a guiding member, one end of said guiding member being pivoted to said seat, the other end of said guiding member being pivoted to an intermediate point of said controlling link, and the other end of said controlling link being in shiftable engagement with said leg-rest whereby movements of said leg-rest are controlled in dependence on movements of said seat.

10. A reclining article of furniture comprising: a support, a structure including a seat and a back-rest rigidly connected with each other, said structure being swingably mounted on said support, stopping means arranged on said support for limiting the sitting position of said structure, a leg-rest pivotally connected with the front portion of said seat, a controlling link pivoted to said support at one of its ends, a guiding member, one end of said guiding member being pivoted to said seat, the other end of said guiding member being pivoted to an intermediate point of said controlling link, and controlling means positioned between the other end of said controlling link and said leg-rest to effect movement of the leg-rest in coordination with said controlling link whereby movements of said leg-rest are controlled in dependence on movements of said seat.

11. A reclining article of furniture comprising: a support, a structure including a seat and a back-rest rigidly connected with each other, said structure being swingably mounted on said support, stopping means arranged on said support for limiting the sitting position of said structure, a leg-rest pivotally connected with the front por-

tion of said seat, a controlling link pivoted to said support at one of its ends, a guiding member, one end of said guiding member being pivoted to said seat, the other end of said guiding member being pivoted to an intermediate point of said controlling link, and a controlling member, one end of said controlling member being pivoted to the other end of said controlling link, and the other end of said controlling member being pivoted to said leg-rest.
